CLAIM

The ornamental design for the digital thermometer, as shown and described.

DESCRIPTION

FIG. 1 shows a perspective view of the front side of the thermometer, including a dark shaded portion, the dark shaded portion indicating a contrast in color between the dark shaded portion and adjacent portions of the thermometer.

FIG. 2 shows a left side view of the thermometer, including a dark shaded portion, the dark shaded portion indicating a contrast in color between the dark shaded portion and adjacent portions of the thermometer.

FIG. 3 shows a right side view of the thermometer, including a dark shaded portion, the dark shaded portion indicating a contrast in color between the dark shaded portion and adjacent portions of the thermometer.

FIG. 4 shows a back view of the thermometer, including a dark shaded portion, the dark shaded portion indicating a contrast in color between the dark shaded portion and adjacent portions of the thermometer.

FIG. 5 shows a front view of the thermometer, including a dark shaded portion, the dark shaded portion indicating a contrast in color between the dark shaded portion and adjacent portions of the thermometer.

FIG. 6 shows a top view of the thermometer; and,

FIG. 7 shows a bottom view of the thermometer.
